[57] CLAIM

The ornamental design for a shield for hypodermic needle, as shown and described.

DESCRIPTION

FIG. 1 is an isometric view of a shield for hypodermic needle showing my new design;

FIG. 2 is a front elevational view of the embodiment of FIG. 1;

FIG. 3 is a top plan view thereof, the bottom being identical;

FIG. 4 is a left end elevational view thereof; and

FIG. 5 is a right end elevational view thereof.

FIG.1

FIG.2

FIG.3

FIG.4
